H. V. HAIGHT

COMPRESSOR UNLOADER

Filed Oct. 14, 1925

UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

COMPRESSOR UNLOADER.

Application filed October 14, 1925. Serial No. 62,398.

This invention relates to compressor unloaders of the step-by-step type, and the objects of the invention are to produce a simple and efficient unloader which is cheap to manufacture and capable of unloading the compressor step-by-step automatically and again loading it, preferably controlled by the discharge pressure.

The invention is applicable to any compressor cylinder whether single or double acting, duplex or compound, and may be termed a "free air" unloader because several of the unloading steps are effected by holding one or more of the inlet valves open. In accordance with this invention, however, the first step of unloading is effected by means of a clearance chamber and clearance valve which forms a simple and convenient means in combination with the inlet valves for obtaining the required number of steps.

The invention is shown in one of its preferred forms in the accompanying drawing, which is a diagrammatic view partly in vertical section and partly broken away, showing the invention applied to a compound compressor.

Referring to the drawings, the low pressure cylinder A and the high pressure cylinder B are provided with the pistons C and D having the piston rods E and F adapted to be driven in any suitable manner from a motor or engine not shown. The discharge G of the low pressure cylinder is connected in the usual manner through the intercooler H to the inlet J of the high pressure cylinder, and the inlet of the low pressure cylinder is indicated at K. The discharge L of the high pressure cylinder is connected to the usual receiver O by the pipe P.

The air head at the head end of each cylinder is provided with a single clearance chamber Q and R, communication between which chambers and their respective cylinders is controlled by the clearance valves S and T, which may be ordinary plate valves adapted to be held open in any suitable manner when required, as by means of the valve openers U and V having fingers W and X adapted to bear against the valves and hold them open. Springs Y and Z normally hold the fingers retracted, and the valve openers are in this instance provided with the pistons a and b in the cylinders c and d, which are connected by pipes e and f to the common pipe g which is in turn connected

through the auxiliary valve h and pipe j to the receiver O.

The cylinders A and B are provided with suitable inlet and discharge valves, which may be of the plate type, and as shown, the inlet valves k and o of the low pressure cylinder are provided with the valve openers p and q similar to those described in connection with the clearance valves. The inlet valves r and s of the high pressure cylinder are also provided with the valve openers t and u of similar construction. The discharge valves v of both cylinders may be of any suitable construction and are shown as plate valves.

The cylinders w of the inlet valve openers at the clearance ends of the cylinders are respectively connected by the pipes x and y to the common pipe z, which is in turn connected to the auxiliary valve 3 and thence through the pipe 4 to the receiver O. The cylinders 5 of the valve openers of the inlet valves on the opposite ends of the cylinders are respectively connected by the pipes 6 and 7 to the common pipe 8, which is connected through the auxiliary valve 9 and pipe 10 to the receiver O.

The auxiliary valves referred to may be of any suitable construction for causing automatic and successive operation of the various valve openers in accordance with the discharge pressure, and it is to be understood that a valve of the type shown in U. S. Patent No. 1,138,278 granted May 4, 1915, to J. H. Castle and W. G. Rogers, may be used, which is so constructed that the valve operates to admit a certain predetermined receiver pressure to the appropriate unloading mechanism until the receiver pressure again falls a certain amount below that required to operate the valve, in which case the valve returns to its original position, allowing the unloading mechanism to exhaust to atmospheric pressure.

On each of the auxiliary valves h, 3 and 100 in the drawing I have indicated the adjustable valve plugs 14 and the spring cups 28 corresponding to similar parts similarly numbered in said patent, it being understood that any other suitable auxiliary valve operating as a pilot valve may be used in the locations indicated by valves h, 3 and 9, since the particular construction of valve forms no part of the present invention.

In the operation of the apparatus let it 110

be assumed that the compressor is operating at full load with all clearance valves closed and the inlet valves functioning normally, since the valve opener cylinders of the valves 5 are all opened to atmosphere through their respective auxiliary valves *h*, *3* and *9*. The auxiliary valves are set to operate at different successively predetermined pressures for three-quarter load, one-half load and no 10 load. When the first auxiliary valve *h* operates to admit pressure to the valve openers of the clearance valves *S* and *T*, at the head end of the cylinders, said clearance valves will be simultaneously opened and each cylinder 15 will operate under three-quarter load. On the next step the auxiliary valve *3* opens and admits pressure to the valve lifter cylinders and the inlet valves *k* and *r* at the head ends of the compressor cylinders, which 20 still further unloads the compressor causing it to operate at one-half load. The clearance valves may continue to remain open, although, if desired, the apparatus could be so constructed that these valves would automatically 25 close at this point. The third step of operation is effected by the auxiliary valve *9* which causes the inlet valves *o* and *s* at the crank ends of the cylinders to be held open while maintaining the inlet valves *k* 30 and *r* open, thus fully unloading the compressor. As the auxiliary valves operate in reverse order the compressor is first placed under one-half load, then three-quarter load, then full load. 35 It is to be understood that any desired number of steps of unloading and loading may be effected, but in this instance the step of one-quarter loading is omitted, for simplicity and for particular application to certain kinds of duty for the compressor. 40

I claim:

1. In a compressor unloader, the combination of a cylinder having heads and a piston, inlet and discharge valves, a single clearance

chamber in the air head at the head end of the cylinder, a clearance valve for said chamber, and means for unloading the compressor in three successive steps only by first opening the clearance valve, then holding an inlet valve open at the head end of the cylinder, and lastly holding an inlet valve open at the crank end of the cylinder for complete unloading.

2. In a compressor unloader, the combination of a cylinder having heads and a piston, inlet and discharge valves, a single clearance chamber in the air head at the head end of the cylinder, a clearance valve for said chamber, and automatic unloading devices responsive to the rise in discharge pressure for unloading the compressor step by step, in three successive steps only, by first opening the clearance valve, then holding an inlet valve open at the head end of the cylinder, and lastly holding an inlet valve open at the crank end of the cylinder for complete unloading.

3. In a compressor unloader, the combination of a cylinder having heads and a piston, inlet and discharge valves, a single clearance chamber in the air head at the head end of the cylinder, a clearance valve for said chamber, and automatic unloading devices responsive to the rise in discharge pressure for unloading the compressor step by step, in three successive steps only, by first opening the clearance valve, then holding an inlet valve open at the head end of the cylinder, and lastly holding an inlet valve open at the crank end of the cylinder for complete unloading, said automatic unloading devices also operating to load the compressor step by step in reverse order as the discharge pressure falls.

In testimony whereof I have signed this specification.

HARRY V. HAIGHT.
